UNITED STATES PATENT OFFICE

LEE H. ADAMSON, OF BEVERLY HILLS, CALIFORNIA

MECHANICAL MOVEMENT

Application filed July 30, 1929. Serial No. 382,224.

This invention aims to provide a mechanical movement for operating a signal on a vehicle, the signal being so actuated and constructed that a person within a closed car may 5 use it to indicate when a left turn is to be made.

It is within the province of the disclosure to improve generally and to enhance the utility of devices of that type to which the present invention appertains.

With the above and other objects in view, which will appear as the description proceeds, the invention resides in the combination and arrangement of parts and in the details 15 of construction, it being understood that changes may be made in the precise embodiment of the invention, within the scope of what is claimed, without departing from the spirit of the invention.

20 In the accompanying drawings:

Figure 1 shows in elevation a part of an automobile door whereunto the device forming the subject matter of this application has been applied, a part of the lining of the door having been removed, in order that certain working parts may be more clearly shown;

Figure 2 is a longitudinal section on the line 2—2 of Figure 1;

Figure 3 is an enlarged elevation showing 30 a portion of the lever and attendant parts;

Figure 4 is a sectional view on the line 4—4 of Figure 3;

Figure 5 is an elevation showing the lever raised from the position of Figure 3;

Figure 6 is a section on the line 6—6 of Figure 5;

Figure 7 is a section taken above one of the bearing brackets;

Figure 8 is a sectional view illustrating 40 means whereby the spiral or screw is connected to the staff which carries the signal;

Figure 9 is a fragmental sectional view illustrating the joint between the signal staff and the screw or spiral;

45 Figure 10 is an elevation showing a ball and socket joint used as a connection between certain parts of the machine.

The numeral 1 marks a support, which may be the front left hand door of an automobile, 50 and in the door 1 there is a shoulder opening

or slot 2 through which the pane 3 of glass slides up and down.

Within the support or door 1 is mounted a frame comprising an upright 4 and a cross piece 5, the parts 4 and 5 being made of wood, 55 if desired. The numeral 6 designates a lever fulcrumed at one end, as shown at 7, on the cross piece 5. The opposite or free extremity of the lever 6 is reduced, as shown at 8.

A two-part bearing 9 is secured to the cross piece 5, and in the bearing 9 the reduced neck 10 (Figure 6) of a shaft 11 is journaled. An offset bearing bracket 12 is attached to the cross piece 5, and in the bracket the shaft 11 is journaled, in spaced relation to the bearing 9. The shaft 11 has a squared end 14 on which a cooperating member or handle 16 is held by a screw 15.

The numeral 17 marks an arm which is held by side plates 18 on the shaft 11, so that 70 when the shaft is rotated by means of the handle 16, swinging movement will be imparted to the arm 17.

Fork pieces 19 are secured to the upper end 75 of the arm 17 and carry a shaft 20 on which an antifriction element, such as a roller 21, is journaled. An inverted U-shaped yoke 22 is provided and the arms and the yoke 22 are pivotally mounted on the shaft 20 between the fork pieces 19, the roller 21 extending into the yoke 22, as Figure 6 will show. The lever 6 slides through the yoke 22 in edge contact with the roller 21.

An upper bearing 23 and a lower bearing 24 are secured to the upright 4. In the horizontal portions of the bearings 23 and 24 (Figure 7) there is a circular opening 25 having oppositely-disposed extensions 26. A signal staff 27 is journaled for rotation in the opening 25 of the upper bearing 23 and carries an arm 28 on which a signal 28a, of any desired kind, is marked. The arm 28 preferably is made of stiff wire, to cut down any resistance when the arm sticks out from the car at right angles to the line of advance of the car. There is a slot 29 in the lower end of the staff 27 and into the slot 29 extends a strip 30. A nut 31 is threaded on the lower end of the staff 27 and has oppositely-disposed seats 32, adapted to receive reduced

90

95

100

5 fingers 33 on the upper end of the strip 30, the fingers 33 being welded in the seats 32, if so desired, a strong union between the strip 30 and the staff 27 being provided. The strip 30 slides in the extensions 26 of the opening 25 in the lower bearing 24. The extensions 26 of the upper bearing 23 have no function, and the circular opening 24 of the lower bearing 24 has no function, but the parts 26 and 25 10 are retained in both of the bearings 23 and 24 to save the cost of making two bearings that are different.

In the strip 30, a twist or spiral 34 is fashioned, and the strip 30, therefore, may be referred to as a screw. The lower end of the strip 30 is connected (Figure 10) by a ball and socket joint 35 with the lever 6, the ball on the joint 35 having a small ear 36 which is provided with an opening 37 wherein the 20 reduced end 8 of the lever 6 is received.

The operator swings the handle 16, thereby rotating the shaft 11, the arm 17 being swung from the solid line position of Figure 1 to the dotted line position of that figure, the 25 yoke 22 pivoting on the shaft 20, the yoke sliding along the lever 6 with the roller 21 in contact with the lower edge of the lever. The end 8 of the lever 6 raises the strip 30, and the strip 30 raises the staff 27, the signal 30 arm 28 being lifted out of the slot 2. The signal arm 28 is lifted rapidly and then is turned slowly until it stands out at right angles to the side of the car, the rotation of the staff 27 and of the strip 30 being brought 35 about as the spiral portion or screw 34 of the strip 30 passes through the reduced parts 26 of the opening in the lower bearing 24, the ball and socket joint 35 permitting the strip 30 to rotate with respect to the ear 36 which 40 is engaged at 37 with the reduced end 8 of the lever 6.

The operation of restoring the parts to the solid line position of Figure 1 involves simply a reversal of the operation hereinbefore 45 described, and need not be dilated upon. For convenience, in claiming the invention, the staff 27 and the strip 30 may be described as a shaft supported for rotation and having a spiral part 34 which cooperates with the bearing 24 to impart rotation to the shaft, it being noted that the staff 27 has a longitudinal movement and a rotary movement in the bearing 23, the strip 30 having a longitudinal movement and a rotary movement in the 50 bearing 24.

I claim:

1. In a mechanical movement, upper and lower bearings, a staff mounted to rotate and to slide longitudinally in the upper bearing, 55 a strip mounted to slide longitudinally in the lower bearing, the strip and the lower bearing having elements which cooperate to impart rotation to the strip when the strip is moved longitudinally, means under the 60 control of an operator for moving the strip

longitudinally, and a nut threaded on the staff and having seats in its edge, the staff being provided in its end with a slot receiving one terminal of the strip, the strip having fingers received in the seat of the nut. 70

2. In a mechanical movement, a bearing, a shaft mounted to rotate and to slide longitudinally in the bearing, the shaft and the bearing having elements which co-operate to impart rotation to the shaft when the shaft is moved longitudinally, a lever, a fulcrum for one end of the lever, means for pivotally connecting the opposite end of the lever with the shaft to impart longitudinal movement to the shaft, a second shaft, means for journaling the second shaft below the lever, an arm secured to the second shaft and located immediately below the lever, whereby that portion of the arm which is mounted on the second shaft will serve as a stop limiting the downward movement of the lever, and mechanism for connecting the arm slidably and pivotally with the lever. 75

3. In a mechanical movement, a bearing, a shaft mounted to rotate and to slide longitudinally in the bearing, the shaft and the bearing having elements which cooperate to impart rotation to the shaft when the shaft is moved longitudinally, a lever, a fulcrum for one end of the lever, means for pivotally connecting the opposite end of the lever with the shaft to impart longitudinal movement to the shaft, a second shaft, means for journaling the second shaft below the lever, an arm secured to the second shaft and located immediately below the lever, whereby that portion of the arm which is mounted on the second shaft will serve as a stop limiting the downward movement of the lever, and mechanism for connecting the arm slidably and pivotally with the lever, said mechanism comprising a U-shaped yoke, a pivot element connecting the yoke to the arm, and an anti-friction member journaled on the pivot element within the yoke, the lever being slideable through the yoke in contact with the anti-friction member. 80

In testimony that I claim the foregoing as my own, I have hereto affixed my signature.

LEE H. ADAMSON. 115
